GAS TURBINE PLANT

Walter Traupel, Winterthur, Switzerland, assignor to Sulzer Frères Société Anonyme, Winterthur, Switzerland

Application February 27, 1945, Serial No. 579,968
In Switzerland June 17, 1944

2 Claims. (CL 60—49)

1

This invention relates to gas turbine plants having at least two turbines.

In gas turbine plants employing circuits open to the atmosphere, it is known to locate, before the compressor turbine and, if necessary, before the useful output turbine as well, throttling members actuated by circuit conditions, for instance, by pressures, and, if necessary, additionally by hand.

In such plants, the working medium may flow through the two turbines in parallel. Any actuating of the throttle members will then alter the distribution of the stream of working medium between the two turbines. This has, of course, the desired effect that the outputs of the turbines are changed, but, on the other hand, it has the undesired effect that the pressure ratios at the turbines also change and the efficiencies of the turbines are thereby adversely affected. This undesired effect is particularly disastrous in the case of the compressor turbine because its output in all gas turbine plants is a multiple of the useful output. The latter is obtained from the plant in the form of a comparatively small surplus output. Consequently, a slight diminution in the efficiency of the compressor turbine means a very considerable reduction in the overall efficiency of the plant.

To eliminate these disadvantages the present invention proposes a novel combination of a circuit of working medium closed off from atmosphere, from which circuit a partial quantity is continuously extracted and in place thereof a make-up quantity is introduced, with at least one turbine driven by the working medium flowing round in the circuit and at least one other turbine driven by the partial quantity extracted from the circuit, combined with a pressure regulator which is influenced by the highest (roughly) pressure of the circuit to adjust the extraction of working medium through the turbine driven by the extracted quantity until the actual value of the highest pressure in the circuit is, within the regulating error of the apparatus, equal to the control value, as at the moment set on the regulator.

With a circuit thus closed off from atmosphere, that quantity of the working medium which flows through the circuit turbine returns to the closed circuit, and must, of necessity, subsequently flow through the turbine driven by the extracted medium before it can flow successively away to atmosphere. Thus viewed, a major portion of the working medium might be said to flow through the two turbines not in parallel, but in series, and

2

this circumstance gives the regulating operation quite another action from the case of the uncomplicated parallel flow of an open circuit.

Moreover, the regulating operation in the closed circuit may not, as in the open, alter the quantity of the working medium fed to the turbine driven by the extracted quantity at the expense of the quantity driving the circuit turbine. Apart from a short fluctuation caused by the volume-capacity of the circuit, the regulator may not through its own operation produce any effect at all on the quantity of working medium so fed. For it represents the quantity extracted, and as such (after deduction of the very slight quantity of fuel) is always equal to the make-up quantity and therefore, just like the latter, depends on the qualities of the particular compressor which draws the make-up quantity from the atmosphere and introduces it into the circuit. But such compressors have a very steep characteristic; their suction volume therefore alters only little if their final pressure is changed.

Consequently the regulator here adjusts the pressure but not the quantity of the extracted medium, and in particular not the quantity flowing to the turbine working with the extracted medium, as is the case with an open circuit. Because of this it here influences the output of the circuit turbine, in that it changes the pressure level of the circuit, and any change in the pressure ratios at the circuit turbine—which as already explained would be a great drawback—is avoided.

Further advantages of the arrangement proposed by the invention are that at the turbine working with the extracted medium the heat drop now available is considerably greater, whilst the temperature on the other hand is essentially lower than at the circuit turbine. A throttle member adjusting the quantity extracted may therefore be designed for a smaller volume, since the specific volumes at lower temperatures are smaller; the lower temperature also greatly facilitates the structural design of the valve. Further, because of the greater heat drop a considerable part of the loss arising through the throttling can be recovered again as output, the lower value of the temperature diminishing the risk that the temperatures in the final stages of the turbine working with the extracted medium become too high.

Further, the invention is based on a recognition that pressure changes occur essentially earlier than changes in speed. For, in consequence of

the energy stored in the gas-content and of the kinetic energy of the turbo rotor a change in pressure of the working medium has a time-lead in comparison with a change in speed in turbo machines subjected to regulating operations. Therefore, if the regulating impulse for adjusting the output is derived from a pressure of the working medium, the stability of the system will be greatly increased.

These advantages of the invention are further not confined either to a definite pressure of the circuit or to a definite output of the turbine worked with the extracted medium, an output corresponding somewhat to that pressure. On the contrary, it is possible to take measures so that the output of the turbine worked with the extracted medium can be adjusted to different levels by altering the setting of the control value for the highest circuit pressure. Plant efficiency thus remains without any perceptible diminution over really wide limits.

Further, measures can be adopted to utilize the turbine working with extracted medium as the useful output turbine. In this way the speed of the circuit turbine is made independent of the speed at which the useful output is required. The speed of the circuit machines is then free to follow and to correspond to the adjusted control value of the moment for the highest circuit pressure, whilst the speed of the turbine working with the extracted medium follows and corresponds to the useful output. If the latter is led, for instance, to a ship's propeller, any regulating of the circuit machine speeds (with the exception of safety devices) will be superfluous.

The invention is now explained more fully with the aid of the drawing, in which:

Fig. 1 shows a gas turbine plant according to the invention.

Fig. 2 illustrates the regulating device used in the gas turbine plant shown in Fig. 1.

The gas turbine plant shown in Fig. 1 works with a circuit of air from which a part is continuously extracted, in return for which a make-up quantity is continuously supplied at another point. The air compressed by the low-pressure compressor 1 passes through the intermediate cooler 2 into the high-pressure compressor 3. The compressed air then flows through the pipe 4 into the heat-exchanger 5, in which it is pre-heated while flowing through the tubes 6. Through the pipe 7 the air passes further to the point 8, at which it is divided up into two parts. A major part passes through the pipe 9 into the gas heater 10, is heated to the highest circuit temperature while flowing over the heat exchange tubes 11 and is then supplied through the pipe 12 to the turbine 13.

The air expanded in the turbine 13 flows through the pipe 14 into the heat exchanger 5 and here gives up part of its residual heat by heat transmission to the air flowing through the heat-exchanger tubes 6. Through the pipe 15 the air passes into the cooler 16, in which a further part of its residual heat is led away in a cooling medium. Through the pipe 17 the air is finally returned to the low-pressure compressor 1, where the circuit recommences.

From the circuit of air described a part is continuously extracted at the point 8 and is supplied through the pipe 18 to the burner 19 of the gas heater 10 as combustion air. The combustion gases flow out of the combustion chamber 20 into the heat exchange tubes 11, whose walls give up the heat to the air of the circuit flowing over

the tubes. Afterwards the combustion gases pass through the pipe 21 into the turbine 22.

To replace the air extracted from the circuit at the point 8, air from the atmosphere is continuously supplied to the circuit by the compressor 23. This make-up quantity is introduced into the heat-exchanger 5 through the pipe 24 at a point 25 at which the air flowing over the heat-exchanger tubes 6 are approximately at the same temperature and the same pressure as the make-up quantity.

The sequence of pressures of the air in the circuit rises from its lowest value at the entry to the compressor 1 to its highest value at the outlet from the compressor 3. While the air flows through the heat-exchangers 5 and 10 and the connecting pipes, a slight drop of the pressure occurs according to the resistance to flow. A large drop of pressure occurs in the turbine 13. The outlet pressure is higher than the inlet pressure to the compressor 1 by the amount required to overcome the resistance to flow in the heat-exchangers 5 and 10 and in the pipes.

The absolute values of the pressure sequence depend on the height of the pressure at entry into the compressor 1, and this in its turn on the height of the delivery pressure of the compressor 23. When this inlet pressure is changed, for instance as a result of a change of speed, the pressures in the whole circuit will change, and the maximum pressure to an even higher extent than the inlet pressure.

The turbine 13 operated by the air flowing in the circuit drives the compressors 1, 3 and 23, while the turbine 22, which is operated by the part quantity extracted from the circuit, acts as a useful output turbine and drives the ship's propeller 27 through a gear 26. The turbine 13 and the compressors 1, 3 and 23 are further coupled to an auxiliary electric motor 28 which serves for starting the plant and for balancing surplus or lacking power.

For the purpose of adjusting the extraction of working medium by the extraction turbine, turbine 22 is equipped with a bypass pipe 29 which bypasses its first stage and in which a flow regulating member 30 is built. The servomotor 31 of this regulating member is influenced by means of the impulse pipe 32 from the regulating device 33. The control of the regulating device is effected by the pressure of the air in the inlet pipe 12 of the turbine 13, transmitted through the pipe 34. With the aid of the lever 35 the control value for the pressure in the inlet pipe 12 of the circuit turbine 13 and thus for the useful output delivered by the turbine 22 working with the extracted medium can be set as required by hand.

A reduction of the cross section of flow freed by the regulating member 30 diminishes the absorption capacity of the useful output turbine 22.

Consequently the useful output certainly falls in the first instant. But the pressures in the circuit increase at once, and continue to do so until the quantity extracted, which flows through the non-bypassed stages of the turbine 22, has again become equal to the quantity continually introduced to the circuit through the compressor 23. The bypassed stages are then flowed through by a larger quantity than before the beginning of the operation, so that the output of the turbine 22 has now already increased. Meanwhile the circuit machines 13, 1 and 3 as well as the compressor 23, begin to run faster in consequence of the higher pressures, and this is followed by a

further increase in the pressures and therefore in the output of the turbine 22. The increase in the quantities of heat required in this operation is at first obtained from the heat capacity, particularly of the heat-exchanging walls of the gas heater 10, 11, and further by increasing the quantity of fuel fed to the burner 19. If the pressure in the inlet tube 12 finally approaches the control value as set at the lever 35, the regulating device begins again to increase the cross-section of the regulating member 30, so that the output of the turbine 22 now increases very essentially. Finally, when the pressure in the inlet pipe 12 has reached the control value as set at the lever 35, the operation comes essentially to rest, but the output of the turbine 22 still continues slowly to increase further until also the temperatures in the plant come to rest.

An initial increasing of the cross-section of flow freed by the regulating member 30 increases the absorption capacity of the useful output turbine 22 and is therefore followed by an operation in the opposite sense to that described above. With the aid of the lever 35 the output desired for the drive of the propeller can thus be set by the regulating device, and in this way the speed of the vessel can also be set.

The compressor turbine 13 has a bypass pipe 36 which bypasses the first stage of the turbine. The flow regulating member 37 in the bypass pipe can be opened by means of the regulating device 33 by influencing the servomotor 39 through the impulse pipe 32, 38 for the purpose of temporarily accelerating the increase of the useful output. By opening the regulating member 37 the absorption capacity of the compressor turbine 13 is increased.

In this way, in as far as at first the volume-capacity of the spaces in the circuit lying between compressor 3 and turbines 13 and 22 and in as far as further the pressure-volume characteristic of the compressors 1 and 3 allow, the output of the turbine 13 may still be further increased for a short time and thereby the acceleration of the machines 13, 1, 3 and 23 be made still greater, and the desired increase of the useful output is hereby attained in a reduced time.

The regulating device 33 (Fig. 2) is influenced by a pressure responsive bellows 40 and which is connected to the pressure pipe 34. With the aid of the lever 35 the control value for the pressure in the inlet pipe 12 can be set by hand and with it the output desired for driving the ship's propeller.

The expansion of the pressure bellows 40 is transmitted to the joint 41 of the lever 42. The joint 43 on the opposite side of the lever 42 is influenced by means of the lever 35 through the curved cam 44, the rod 45 and the spring 46. The position of the middle joint 47 of the lever 42 is thus determined by the position of the lever 35 and the expansion of the pressure bellows 40.

The control valve 49 is connected to the joint 47 through the linkage 48 and by it the supply of pressure medium from the pipe 50 to the servomotor 52 and the discharge from the servomotor to the discharge pipe 51 are controlled. The piston 53 of the servomotor is connected on the one hand through the rod 54 to the drag device 55 and on the other hand through the spring 56 to the valve control member 57 in the valve casing 64. The piston 58 of the drag device separates two cylinder spaces from each other which are connected through a pipe 60 provided with a throttling point 59. The valve 57 controls the supply of a pressure medium from the pipe 61

or its discharge into the pipe 62. The control space 63 of the valve casing 64 is connected through the control pipe 32 to the servomotor 31 and through the control pipe 38 to the servomotor 39.

The servomotor 31 has a piston 65 upon which the force of the spring 66 acts from below and the pressure of the control medium in the space 67 from above. Arranged in the servomotor 39 is a piston 68 which the force of the spring 69 acting from below and the pressure of the control space 70 acting from above keep in equilibrium. The springs 66 and 69 are of such dimensions that the regulating member 37 is only lifted from its seat when the regulating member 30 is pressed against its seat and completely interrupts the flow through the pipe 29.

If the lever 35 is displaced in the +direction of the arrow 71, the rod 45 is moved in the +direction of the arrow 72. The spring 46 is then compressed, so that the joint 43 is also displaced in the +direction of the arrow 72 as far as allowed by the displacement of the liquid in the drag device from the underside of the piston 58 to the upper side through the throttling point 59. As the joint 41 at first remains at rest the control valve 49 moves in the +direction of the arrow 73. Now pressure medium flows from the pipe 50 through the pipe 74 into the space of the cylinder 52 situated below the piston 53. The piston is displaced in the +direction of the arrow 76 and the liquid then subjected to pressure in the upper cylinder space is led off through the pipe 75 to the discharge pipe 51.

By the displacement of the servomotor piston 53 the already existent tensile stress of the spring 56 is increased and the control valve is drawn upwards. A connection is thus established between the supply pipe 61 and the control space 63. By the supply of pressure fluid the control pressure in the space 63 is raised until the increased pressure loading on the valve control member 57 in the valve casing 64 balances the increased tensile stress of the spring 56 in the middle position of the valve, the control openings of the pipes 61 and 62 being closed.

The increased control pressure in the space 63 is transmitted through the pipe 32 into the control space 67 of the servomotor 31 and through the pipe 38 into the control space 70 of the servomotor 39. The increased control pressure in the space 67 presses the piston 65 downwards, so that the cross-section of flow freed by the regulating member 30 is reduced. In this way the resistance to flow through the useful output turbine is increased and its volumetric absorption capacity for working medium is decreased.

If the increase in the control pressure in the pipes 32 and 38 after the complete closing of the regulating member 30 is able to overcome the pressure of the spring 69 in the servomotor 39, the regulating member 37 is raised from its seat. The result is an increased absorption capacity of the compressor turbine. The speed of the compressor turbine is raised more rapidly, so that the compressors also raise the sequence of pressures in the circuit more rapidly and thus the useful output is increased in a shorter period of time.

Overregulation and an oscillation of the regulation involved with this is prevented with the aid of the drag coupling 55, which takes effect as a yielding return means and at the very beginning of the regulating adjustment begins a return motion. In this way the control value set can be maintained in actual values without any lasting irregularity. During the displacement of the

servomotor piston 53 the drag piston 58 is displaced in the +direction of the arrow 76. The joint 43 of the lever 42 is thus displaced in the direction opposite to the original direction of displacement, so that the control valve 49 is again moved back towards its middle position in which the control openings of the pipe 74 and 75 are closed.

The final return of the regulating process is then effected through the plant itself, while the return motion of the yielding device again ceases to be effective. When the sequence of pressures in the circuit is raised, the pressure responsive bellows 40 expands. The joint 41 of the lever 42 moves upwards. The opposite joint of the lever is forced into the position in which the spring 46 is unloaded. The regulating device comes to rest when the pressure bellows 40 has brought the control valve 49 into the middle position with the spring 46 unloaded. The height of the sequence of pressures in the circuit then corresponds to the control value set by the lever 35. As a result of the yielding return motion a single allotted value for the sequence of pressures and thus also for the useful output corresponds to each position of the lever at any time.

If there is a rise of actual pressure above its control value, by means of the pressure bellows 40 the joint 41 is displaced in the -direction of the arrow 73. The control valve 49 then connects the pipe 50 to the pipe 75. The piston 53 of the servomotor 52 is displaced in the -direction of the arrow 76 and the spring 56 is unloaded, so that the control valve 57 also slides downwards. Fluid can escape from the control space 63, so that the control pressure in the pipes 32 and 38 is reduced correspondingly. In this way the cross-section of flow at the valve 30 is increased and a greater quantity of working medium is extracted from the circuit. The speed of the compressor turbine and the compressors driven by it is decreased, so that the sequence of pressures in the circuit is lowered, until it again corresponds to the control value set by the lever 35.

If the sequence of pressures in the circuit falls below the control value, the valve 49 is displaced in the +direction of the arrow 73 with the aid of the bellows 40, the lever 42 and the linkage 48. The servomotor piston 53 is then raised and the spring 56 is loaded to an increased extent. According to the increase of load, an increase of pressure presents itself in the control pipes 32 and 38, whereupon the cross-section freed by the valve 30 is diminished and in given cases the valve 31 is raised from its seat. The decreased extraction of working medium from

the circuit through the pipe 28 dams up the working medium in the circuit, raising the pressure and thus the speed of the compressor turbine and of the compressors until the pressure has again reached the control value required.

For diminishing the output the lever 35 is displaced in the -direction of the arrow 71. Corresponding regulating processes then take effect, but in the opposite direction. The sequence of pressures in the circuit is lowered, and accordingly the output of the useful output turbine is decreased.

The point at which the pressure impulse is given for the purpose of maintaining the required state of pressure may also be situated at other points in the circuit, at which the pressure has a lower value.

I claim:

1. In a gas turbine plant having a circuit for working medium closed off from the atmosphere from which circuit a quantity of working medium is continually extracted and into which a substantially constant make-up quantity is continually introduced and which plant includes at least two turbines, one driven by the working medium flowing round in the circuit and the other driven by the quantity extracted from the circuit, the combination of a pressure actuated servo regulator adjustable over a range of control value settings including actuating means responsive to the approximately highest pressure of the circuit and regulating means arranged to adjust the manner of extraction of the substantially constant quantity of working medium passing through the turbine driven by the extracted quantity, said actuating means causing said regulating means to adjust to bring the actual value of that highest pressure equal to the control value set on said regulator.
2. The combination of claim 1 in which the turbine working with the extracted quantity delivers the plant useful output.

WALTER TRAUPEL.
